PRESSURE ACTUATED SWITCH

Charles Jardine, Toledo, Ohio, assignor to Moto
Meter Gauge & Equipment Corporation, Toledo,
Ohio, a corporation of Delaware

Application June 17, 1932, Serial No. 617,911

7 Claims. (Cl. 200—83)

This invention relates to pressure actuated switches, and more particularly to devices of this character adapted to make or break a circuit when the pressure to which the device is responsive varies from a predetermined setting. While the invention is of general application, it is particularly useful in connection with the lubrication system of an internal combustion engine, for energizing a circuit including an alarm such as a signal light, when the oil pressure falls below a satisfactory operating pressure.

Objects of the invention are to improve the construction and operation of devices of this character, to render the same inexpensive to manufacture, convenient to install and adjust, and otherwise better adapted for the purposes set forth.

In the drawing, the single figure is a cross-section through a pressure actuated switch according to the preferred embodiment of the present invention, it being understood that various modifications may be made therein without departing from the scope of the appended claims.

The switch comprises a casing 10 having a pressure chamber 12 and an insulator 14, a diaphragm 15 being mounted between the insulator 14 and the pressure chamber. A fixed contact 16 is separated from the diaphragm 15 by the insulator 14, and a movable contact 17 passes through the insulator 14 for actuation by the diaphragm 15.

The insulator 14 is preferably a molded block of phenol condensation product, and the fixed contact 16 is preferably a hollow metal cylinder having an end wall 18 embedded in this block and provided with an aperture 20. A passage 22 is formed in the insulator 14, aligned with the aperture 20.

In the form shown, the movable contact 17 has a head inside the bore 23 of the fixed contact, and a stem passing through the aperture 20 and passage 22, terminating adjacent the diaphragm 15. The passage 22 thus forms a guide for the stem of the movable contact 17, and the aperture 20 is provided with sufficient clearance to cause the contacts to engage only at the outer rim of the head of the contact 17 and the inner rim of the wall 18.

The outer end of the bore 23 is threaded to receive a threaded plug 24, and a helical coiled spring 25 is interposed between this plug and an insulating disk 26 bearing on the head of the contact 17. The plug 24 may thus adjust the pressure with which the spring 25 resists the action of the diaphragm 15.

The casing 10 preferably comprises a base portion 28 and an annular wall portion 29. A compressible insulating gasket 30 is interposed between the rim of the diaphragm and the base portion 28 outside of the chamber 12. The diaphragm 15 has rim portions 32 turned up to insure contact thereof with the wall portion 29. When the parts are assembled, the rim of the wall portion is crimped or spun over the insulator 14, 65 and retains the gasket 30 compressed.

A recess 33 is formed in the face of the insulator 14 adjacent the diaphragm and aligned with the chamber 12. The base portion 28 has a hollow threaded boss 34, which is screwed into the source of pressure, so that the pressure to which the switch is responsive is supplied to the chamber 12.

A terminal 35 is connected to the contact 16, by a screw 36 passing through the same and engaging the outer end of the threaded bore 23. This terminal connects the contact 16 to the source of electrical power and the circuit to be controlled by the switch, including a ground, and the boss 34 is grounded so that the circuit is broken only by the contacts 16 and 17 being separated by the action of the diaphragm.

From the foregoing description, it will be obvious that when the pressure in the chamber 12 exceeds the pressure to which the spring 25 is adjusted by the plug 24, the diaphragm moves upwardly, forcing the stem of the contact 17 upwardly and thereby lifting the head thereof out of engagement with the rim of the wall 18. When the pressure falls below the desired critical setting, the spring 25 forces the head of the contact 17 into engagement with the wall 18 and thus completes the circuit to the alarm or other device controlled by the switch.

The diaphragm 15 may be constructed of very flexible material, and the spring 25 may be so selected or adjusted that the force exerted by the spring is only slightly in excess of the resistance of the diaphragm to deflection. With this arrangement a very small pressure of the order of 5 to 10 pounds per square inch on the underside of the diaphragm causes an initial movement and consequent opening of the electrical circuit. The diaphragm engages the underside of the insulator 14 before the elastic limit thereof is reached, so that over pressures of around 500 to 600 pounds per square inch cannot injure the diaphragm.

I claim:

1. In a pressure actuated switch, a casing having a pressure chamber, a molded insert in said

casing, a diaphragm between said insert and said chamber, a hollow contact having an end wall embedded in said insert and spaced from said diaphragm, and a movable contact cooperating with said end wall and passing through said insert for actuation by said diaphragm.

5. In a pressure actuated switch, a casing having a pressure chamber, an insulator associated with said casing, a diaphragm between said insulator and said pressure chamber, a hollow contact having an end wall associated with said insulator and spaced thereby from said diaphragm, a movable contact having a head in said hollow contact and means actuated by said diaphragm for moving said movable contact.

10. In a pressure actuated switch, a casing having a pressure chamber, a molded insert in said casing, a diaphragm between said insert and said chamber, a hollow contact having an end wall embedded in said insert and spaced from said diaphragm, a movable contact having a head in said hollow contact and a stem passing through said end wall and said insert for actuation by said diaphragm.

15. In a pressure actuated switch, a casing having a pressure chamber, an insulator associated with said casing, a diaphragm between said insulator and said pressure chamber, a hollow cylindrical contact separated from said diaphragm by said insulator, a movable contact having a head within said hollow contact, insulated means in said hollow contact urging said head toward said diaphragm, and means actuated by said diaphragm for moving said head against the action of said means.

20. In a pressure actuated switch, a casing having a pressure chamber, a molded insert in said casing, a diaphragm between said insert and said chamber, a hollow cylindrical contact having an apertured end wall embedded in said insert, a

movable contact having a head within said hollow contact and a stem passing through said aperture and said insert for actuation by said diaphragm, insulated means in said hollow contact urging said head against said wall, and an adjustable abutment for said means closing said hollow contact.

25. In a pressure actuated switch, a casing having a base portion and cylindrical wall, said base portion having a recess formed therein, said casing having a passage communicating with said recess, an insulator in said casing, a diaphragm between said insulator and said base portion, a gasket between said diaphragm and said base portion, the rim of said wall being crimped over said insulator to clamp said gasket between said diaphragm and said base portion, a fixed contact spaced from said diaphragm by said insulator, and a movable contact cooperating with said fixed contact and passing through said insulator for actuation by said diaphragm.

30. In a pressure actuated switch, a casing having a pressure chamber, a molded insert in said casing, a diaphragm between said insert and said chamber, a cylindrical contact having a longitudinal bore threaded at its outer end and terminating in an inner end wall embedded in said insert and having an aperture therein, said insert having a guide passage aligned with said aperture, a movable contact having a head within said bore and a stem passing through said aperture and slidably in said guide passage, an insulating disk in said bore engaging said head, a plug in the threaded portion of said bore, a compression spring in said bore between said plug and said disk, a screw threaded in the outer end of said bore, and a terminal clamped between the head of said screw and the outer end of said hollow contact member.
